CONTAINER VENT

Paul T. Radtke, Cottage Grove, Oreg.

Application June 29, 1943, Serial No. 492,759

3 Claims. (Cl. 220—44)

The present invention relates to new and useful improvements in air vents for liquid pouring containers, and has for its primary object to provide, in a manner as hereinafter set forth, a device of this character comprising novel closing and sealing means.

Other objects of the invention are to provide a container vent of the aforementioned character which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a container equipped with a vent constructed in accordance with the present invention.

Figure 2 is a vertical sectional view through the container, showing the vent in side elevation, the lower end portion of the tube being broken away in section.

Figure 3 is a view in longitudinal section through the upper portion of the vent.

Figure 4 is a cross sectional view through the upper portion of the vent.

Figure 5 is a detail view in elevation of the lower end portion of the tube.

Referring now to the drawings in detail, it will be seen that the embodiment of the invention which has been illustrated comprises an elongated housing which is designated generally by reference numeral 1, which housing may be of any desired dimensions and material. The housing 1 is fixed in any suitable manner on the top 2 of a pouring container 3 adjacent the filler neck 4 thereof.

In the embodiment shown, the housing 1 is substantially square in cross section, as illustrated to advantage in Figure 4 of the drawings. Extending longitudinally into the housing 1 from the end wall 5 thereof is an air intake neck 6, the inner end of which is formed to provide a seat 7. Depending from the bottom 8 of the housing 1, adjacent the intake 6, is a substantially conical flange 9. The flange 9 has fixed therein a substantially conical seat 10 which is swaged or otherwise suitably formed on the upper end of a tube 11.

The tube 11 extends downwardly at an inclination into the container 3 to a point adjacent the

bottom thereof. This tube 11 terminates in a bevelled lower end portion 12 which is secured against the wall of the container 3 by a bracket 13. A notch 14 in the lower extremity of the tube 11 provides communication between said tube and the container 3.

At a point in longitudinally spaced relation from the flange 9, the bottom 8 of the housing 1 is further provided with a depression 15. The depression 15 is for the reception of a ball valve 16 which is operable in the housing 1. The ball valve 16, when in operative position, is engaged with the seats 7 and 10 for closing the air intake 6 and the tube 11.

15 The end walls 5 and 16 of the housing 1 have formed transversely in their upper portions slots 17. The slots 17 accommodate a downwardly curved or bowed spring 18 which is mounted longitudinally in the upper portion of the housing 1 and which is engaged under tension at all times with the ball valve 16. The spring 18 terminates in downturned end portions 19 for securing said spring in position.

It is thought that the operation of the device 25 will be readily apparent from a consideration of the foregoing. Briefly, with the ball valve 16 in the position shown in Figure 3 of the drawings, the vent is closed and sealed. It will be noted that the lower end of the tube 11 is positioned at 30 the side of the container which is remote from the pouring spout 20 thereof. When the liquid is to be poured, the container 3 is tipped in the usual manner for causing said liquid to flow thru the spout 20. A finger or suitable instrument is 35 inserted in the opening 6 for disengaging the ball valve 16 from the seats 7 and 10 against the tension of the spring 18 and moving said ball valve into the recess 15. Thus, air from the atmosphere is free to enter the container 3 through the tube 11. When the container is returned to an upright position after the pouring operation, the spring 18 is pressed or flexed downwardly at a point adjacent the end wall 16 in a manner to eject or squeeze the ball valve 16 out of the depression 15 and force said ball valve toward the end wall 5 for engagement with the seats 7 and 10, thus again closing and sealing the vent.

It is believed that the many advantages of a vent constructed in accordance with the present 50 invention will be readily understood, and although a preferred embodiment of the device is as illustrated and described, it is to be understood that changes in details of construction may be resorted to which will fall within the scope of the invention as claimed.

What is claimed is:

1. A container vent comprising an elongated trough-like housing, a tube communicating with the bottom of the housing, a ball valve mounted in the housing to roll along the same in opposite directions for opening and closing the tube, and a leaf spring in the housing yieldingly urging the ball downwardly in said housing, said spring having an end manipulative to flex the spring and cause the same to urge the ball in a direction to close said tube.
2. A container vent comprising an elongated housing for mounting on a container, a tube connected to the bottom of the housing and extending into the container, said housing having a bottom depression therein, a ball valve mounted in the housing to roll along the same in opposite directions into closing relation to said tube and seating relation to said depression, respectively, and a leaf spring mounted longitudinally in the housing and engaged with the valve for yieldingly urging said valve downwardly, said

spring having an end manipulative to flex said spring and cause the same to force the ball out of sealing relation to said depression.

3. A container vent of the character described comprising an elongated housing for mounting on top of a container, a tube including a conical seat on one end connected to the bottom of the housing, said bottom of the housing having a depression therein at a point in longitudinally spaced relation to the tube, an air intake neck extending into the housing and including a seat on its inner end adjacent the first-named seat, a ball valve operable longitudinally in the housing and engageable, when in operative position, with the seats for closing and sealing the air intake neck and the tube, said valve, when in inoperative position, being engageable in the depression, and a spring in the housing engaged with the ball for yieldingly urging said ball on the seats or into the depression.

PAUL T. RADTKE.
